UNITED STATES PATENT OFFICE.

MILTON H. SABIN, OF NEW YORK, N. Y.

DESIGN FOR A WATCH BRACELET.

Application filed July 19, 1926. Serial No. 18,401. Term of patent 3½ years.

To all whom it may concern:

Be it known that I, MILTON H. SABIN, a citizen of the United States, residing at New York, in the county of New York and State of New York, have invented a new, original, and ornamental Design for a Watch Bracelet, of which the following is a specification, reference being had to the accompanying drawing, forming part thereof.

The figure is a plan view of a watch bracelet, the outline of a conventional watch being illustrated in dotted lines.

I claim:

The ornamental design for a watch bracelet as shown.

MILTON H. SABIN.
